CABINET SINK

Harry R. Trout and Frederick M. Hill, Pittsburgh, Pa., assignors to American Radiator & Standard Sanitary Corporation, Pittsburgh, Pa., a corporation of Delaware

Application October 8, 1954, Serial No. 32,598

Term of patent 14 years

(Cl. D33—19)

The figure is a perspective view showing one side and the front of the cabinet sink, embodying our new design, the opposite side being substantially the same in appearance as the side shown.

We claim:

The ornamental design for a cabinet sink, substantially as shown and described.
